[57] CLAIM

The ornamental design for a table, as shown and described.

DESCRIPTION

FIG. 1 is a top plan view of a table showing my design;

FIG. 2 is a bottom perspective view;

FIG. 3 is a side perspective view;

FIG. 4 is a top perspective view; and

FIG. 5 is an end perspective view thereof.

The side and end of the table not shown are like the side and end shown in FIGS. 3 and 5, respectively.

FIG. 1

FIG. 2

FIG. 4

FIG. 5
